UNITED STATES PATENT OFFICE.

GEORGE E. SHAW, OF CHICAGO, ILLINOIS, ASSIGNOR TO THE SHAW TELEPHONIC COMPANY OF AMERICA, OF SAME PLACE.

TELEPHONIC TRANSMITTER.

SPECIFICATION forming part of Letters Patent No. 270,136, dated January 2, 1883.

Application filed February 23, 1881. (Model.)

To all whom it may concern:

Be it known that I, GEORGE EDWIN SHAW, of Chicago, in Cook county, of the State of Illinois, have invented new and useful Improvements in Telephonic Transmitters, of which the following is a specification, reference being had to the drawings filed and the letters and figures marked thereon, forming a part of the said specification, in which—

10 Figure 1 is an elevation; Fig. 2, a vertical cross-section, showing the bar-magnet suspended; Fig. 3, a similar section, showing the bar-magnet supported; Fig. 4, a similar section, showing the position of an adjustable armature; Fig. 5, a detail showing the platina point attached to the diaphragm, also the compass J; Fig. 6, a detail showing the position of the radial magnets G G.

15 My improvements pertain to the class of telephonic instruments known as "microphones," having a diaphragm in connection with a platina point and a block of carbon, which constitute the electrodes.

20 My invention consists in supporting one of the electrodes of a microphone in contact with the other electrode by the attraction or repulsion existing between permanent magnets. This I do by freely pivoting and suspending at the upper end a bar-magnet or a bar of any 25 material, the free end of which is made susceptible of magnetic influence by attaching thereto a magnet or magnetic material; or the magnet or bar may be supported by resting its lower end on a base for the purpose of holding 30 said magnet or bar in front of the electrode attached to a diaphragm, so that an electrode attached to the magnet or bar will, when in proper position, make contact with the electrode attached to the diaphragm. The magnet or bar is held in working position by the 35 attraction or repulsion exerted on its free end by permanent magnets or magnetic material placed radially about its free end; or the magnet may be held in its working position and 40 contact of the electrodes regulated by the attraction of said magnet for an armature of steel or iron secured to the frame and adjusted by a suitable screw. It is obvious that if the 45 free end of the bar is terminated with an armature only there must be magnets to hold it in adjustment, while if the bar is terminated

55 with a magnet or is itself a magnet it may be retained in its working position by the attraction or repulsion of other magnets or pieces of magnetic material placed radially about its free end.

60 In the drawings, A indicates the diaphragm; B, the platina point or one of the electrodes; C, a front plate or door of a microphone; D, the oscillating magnet or bar; E and E, brackets; E', a supporting-base for the magnet or bar; E'', a staple or guide around the top of the magnet; E''', a bridge or bracket which supports one of the magnets or pieces of magnetic material; F, the block of carbon or the 65 electrode attached to the magnet or bar; G', an armature attached to the frame; G G, adjustable permanent magnets or bars of magnetic material; H, a battery-wire; J, a pressure bar or spring; K, a wire or its equivalent 70 attached to one of the electrodes; a b, disks or cleats for attaching the electrode to the diaphragm, also serving to hold the wire K or its equivalent to said electrode; d, a rubber gasket or band; e, clamps or binders for fastening 75 the diaphragm to the frame or door of microphone; n and s, north and south poles of the permanent magnets.

75 The magnet or bar D, as shown in Fig. 1, is held in suspension at the upper end by two 80 points or trunnions from a projecting bracket, E, which is attached to the frame C, so as to allow the lower end of said magnet or bar D to swing free; or it may be supported at the lower end, as shown at E', Fig. 3, allowing the 85 upper end to oscillate freely in a wire staple, E'', the magnet or bar D in either of the devices shown being held in its working position, so as to bring the electrode F, attached to the magnet or bar D, into contact with the 90 electrode B, attached to the diaphragm A, by the attraction or repulsion of the magnets or pieces of magnetic material G G, which are placed radially about the free end of said magnet or bar D. The magnet or bar D is provided with a block of carbon, F, or its equivalent, which is attached to the magnet or bar D in any suitable manner, and is placed upon the magnet or bar D opposite the platina point B, which is attached to the diaphragm A, the 95 magnets G G being so arranged that one of them is held in its position by passing it

through a hole in the frame C, the other magnet being supported in its position by a bracket or bridge, E''. The electric battery current (battery not shown) is conducted by the wire H to the carbon F, to which wire H is attached in any suitable manner. The magnet or bar D, whether in the suspended or supported form, is at the free end adjusted in its working position by means of the attraction or repulsion of the poles of the magnets or pieces of magnetic material G, G acting on its free end. These radial magnets are adjustable by moving them to or from the free end of the suspended or supported magnet or bar D, and thus the force of contact of the electrodes is regulated.

Attached to the frame C is a spring or compress, J, the under side of the free end of which is provided with a pad of any suitable non-conducting material, and rests upon the diaphragm A for the purpose of holding the wire K or its equivalent firmly upon the diaphragm A. Said wire K is attached to the electrode B, and passes under the pad J and on the diaphragm A, and from thence is conducted to the ordinary induction-coil. (Coil not shown.) Said compress J also acts as a damper to tone the vibrations of the diaphragm. The compress J is secured to the frame C by a suitable screw, which it is obvious serves to adjust its pressure upon the diaphragm. Said diaphragm, when made of mica, is pierced at or near its center to receive the platina point or electrode B, which is secured to it (the diaphragm) by the two metal disks or cleats a b. Said disks or cleats also serve to hold the wire K or its equivalent to the electrode or platina point B. The periphery of said diaphragm A is surrounded by a rubber gasket or band or any suitable non-conducting material, and is held upon the frame C by suitable clamps, e, or in

any manner that will hold it firmly to the frame C, the frame C being provided with an aperture, c', for the purpose of conveying sounds to the diaphragm A. The microphone thus described is intended to be used in a 45 closed circuit.

Having thus described the microphone and its construction, what I claim as new and as my invention, and desire to secure by Letters Patent, is—

1. In a microphone, a diaphragm carrying one electrode, in combination with a bar susceptible of magnetic induction, freely supported, and carrying another electrode, and two other bars acting magnetically upon the supported bar, so as to attract or repel the same in opposite directions, substantially as described.

2. In a microphone, a bar-magnet carrying an electrode, and pivoted at one end so as to allow the other end to freely move, in combination with a diaphragm carrying another electrode, and adjustable radial magnets arranged, as shown, to act on the free end of said bar-magnet, so as to attract or repel the same in opposite directions, for the purposes described, and substantially as set forth.

3. In a microphone, a diaphragm of mica, pierced to receive an electrode, in combination with such electrode, a bar-magnet carrying another electrode, and pivoted at one end so as to allow the other end to freely move, and adjustable radial magnets acting on the free end of said bar-magnet, so as to attract or repel the same in opposite directions, substantially as described, and for the purposes set forth.

GEORGE EDWIN SHAW.
